(57) **CLAIM**

The ornamental design for a sensor patch, as shown and described.

DESCRIPTION

FIG. 1 is a perspective view of a sensor patch showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The dash lines in the end of the cord depict symbolic break lines. The symbolic break lines and any portion of the article beyond what is shown in the drawings form no part of the claimed design. The rest of the dash lines in the drawings depict portions of the sensor patch that form no part of the claimed design.
